WINE BOTTLE RACK

Michael Lax, New York, N.Y., assignor to Julie Pomerantz, Inc., New York, N.Y.

Filed May 26, 1972, Ser. No. 257,472

Term of patent 14 years

Int. Cl. D6—99

U.S. Cl. D7—71

FIG. 1 is a perspective view of a wine bottle rack showing my new design;

FIG. 2 is a top plan view thereof; and

FIG. 3 is an end elevational view.

I claim:

The ornamental design for a wine bottle rack, substantially as shown.
